UNITED STATES PATENT OFFICE.

LEWIS S. BIXLER, OF FREEMANSBURG, PENNSYLVANIA, ASSIGNOR TO
CHARLES BOND, OF ASHBOURNE, PENNSYLVANIA.

DESIGN FOR A SHAFT-BEARING HANGER.

SPECIFICATION forming part of Design No. 35,208, dated October 22, 1901.

Application filed April 1, 1901. Serial No. 53,964. Term of patent 14 years.

To all whom it may concern:

Be it known that I, LEWIS S. BIXLER, a citizen of the United States, residing in Freemansburg, Pennsylvania, have invented and produced a new and original Design for a Shaft-Bearing Hanger, of which the following is a specification.

My design for a shaft-bearing hanger is fully shown in the accompanying drawings, in which—

Figure 1 is a side elevation of the hanger. Fig. 2 is a transverse section of the same, and Fig. 3 is an inverted plan view on the line *a a*, Fig. 1.

My design consists in a hanger shaped substantially as shown in the accompanying drawings, wherein the hanger has opposite side webs 1, shaped as hereinafter described and vertical as to their lower portions and curved outwardly at the top, these side webs being connected by an upper transverse web 2, a central transverse web 3, and a bottom yoke 4, the hanger also having at the top projecting head portions 5, and the side webs 1 have flat outer faces and recessed enlargements 6, 9, and 12, formed, respectively, upon the webs 1 and 3 and yoke 4. These enlargements do not project either beyond the inner or outer lines of said side webs or yoke, and

consequently do not detract from the symmetry of outline of these main members of the hanger. The enlargements 6 are formed upon the webs 1 inside of the outer ribs of said webs, and each of said enlargements has formed in its inner face a rectangular recess 7, an elongated opening 8 extending from this recess through the web. The central enlargement 9 upon the middle web 3 has formed in its lower face a rectangular recess 10, from which an elongated opening 11 extends upwardly through the web. The yoke 4 has in the upper face of the central enlargement 12 a recess 13, from which an opening 14 extends to the bottom of the yoke.

Having thus described my invention, I claim and desire to secure by Letters Patent—

The design for a shaft-bearing hanger, substantially as described, and as shown in the accompanying drawings.

In testimony whereof I have signed my name to this specification in the presence of two subscribing witnesses.

LEWIS S. BIXLER.
